UNITED STATES PATENT OFFICE.

ISAAC G. LUNDAY AND CALTON G. ANGLIN, OF HICKORY FLAT, ALABAMA.

DESIGN FOR GRAVE-COVERINGS.

Specification forming part of Design No. **8,040**, dated February 2, 1875; application filed December 31, 1874.
[Term of Patent 7 years.]

To all whom it may concern:

Be it known that we, ISAAC G. LUNDAY and CALTON G. ANGLIN, of Hickory Flat, in the county of Chambers and State of Alabama, have invented a Design for Grave-Covering, of which the following is a specification:

The drawing is a perspective view.

The invention relates to the form, configuration, and aspect of a grave-covering; and consists in a design therefor, substantially as hereinafter described and claimed.

A represents the supporting-stone, that may be flush with the top of the grave, while B is the enlarged base, and C D successively

smaller slabs. Upon the highest of these, and at the head of the grave, is erected the column, shaft, or monument, E.

Having thus described our invention, what we claim as new, and desire to secure by Design Patent, is—

The design for the grave-covering, shown and described.

ISAAC G. LUNDAY.
CALTON G. ANGLIN.
